PERFORATING APPARATUS

Joseph G. Pessina, St. Louis, Mo., assignor to
 Emro Manufacturing Company, Incorporated,
 St. Louis, Mo.

Application May 25, 1949, Serial No. 95,280

6 Claims. (Cl. 164—90)

1

This invention relates generally to perforating apparatus adapted to simultaneously provide a pair of apertures in material subjected to the action thereof, said apertures being oppositely disposed, and each equidistant from a selected point designated by an indicating mark, or the like, visually appearing on the material aforesaid.

More particularly, the invention pertains to apparatus adapted to accurately provide a pair of apertures at predetermined points in the periphery of an endless band of material.

More specifically, the instant apparatus is directed to perforating the head band of a uniform cap in the course of the manufacture thereof.

The type of uniform cap herein contemplated, includes a head band, a vizor, a crown portion, and a strap, either ornamental or otherwise, normally extending around a portion of the periphery of said band at the front, and slightly above the upper margin of the vizor.

Straps or braids of this nature are well known, they appear, for example, on dress caps for army personnel, students of military academies, theater and hotel doormen, and so on. In military parlance they are termed chin straps.

Generally, these straps are permanently, or removably, secured at each end thereof to the head band adjacent the end of the vizor by means of a screw or other fastener element.

However, the present invention is not concerned with the fastening elements, but is primarily directed only to that step in the cap manufacturing process which comprises the formation of apertures in the head band to receive them.

In the manufacture of uniform caps, the head band is initially separately formed to provide an annulus including for example an inner sweat band, an outer cloth band and a central flexible but semi-rigid band, said bands being secured together along their top and bottom edges in any suitable manner.

Heretofore, as far as I am aware, the only method employed to obtain the pair of perforations referred to, has been to provide a notch or other indicating mark on the band, manually measure the required distance in either direction from said mark, and thereafter subject the band to the action of a punch press, first on one side, then on the other.

Besides being a laborious and slow process, inaccuracies have been almost unavoidable. It is understood of course, that all the straps for a quantity of caps to be produced, are of identical length, so that it is obviously of prime importance

2

to have the spacing of the perforations commensurate with the length of the bands.

Further, since in some styles of uniform caps it may be desirable to provide said perforations near the bottom edge of the head band, in others at the center or slightly above the center thereof, it should be evident that additional measurements are required, and that invariably the resulting horizontal plane of the perforation on one side of the band is higher or lower than that on the opposite side, that is, when the measurements are manually made, as heretofore.

The principal object of the present invention therefore, is to provide a device which is adapted to overcome all of the disadvantages set forth above; which is simple in operation and requires little skill on the part of an operator; and which may attain its objectives by either manually operable or mechanically operable means.

20 In a general summary of the invention, the device may be said to include a pair of spaced substantially rectangular blocks mounted on a stationary support; a semi-circular head band supporting member removably secured to said blocks; a pointer, and a plurality of auxiliary gauge members adjustably mounted on said supporting member; a slot in each said block for the reception of a portion of the head band; a primary gauge assembly adjustably mounted on each block for positioning said band in the slot; a pair of oppositely disposed perforating assemblies adapted to perforate the head band at two points simultaneously; and cam and lever means for motivating the perforating assemblies at the will of the operator.

30 In the detailed description to follow, certain advantages not hereinbefore specifically set forth will become apparent, reference being had also to the drawings, wherein is illustrated a preferred embodiment of the invention.

40 In said drawings:

Fig. 1 is a top plan view of an apparatus incorporating the present invention, mounted on a portion of a table, bench, or the like;

Fig. 2 is a front elevational view thereof;

Fig. 3 is a right side elevational view thereof, the supporting table being shown partly in section;

Fig. 4 is a vertical sectional view, on an enlarged scale, taken on line 4—4 in Fig. 1, the parts being shown in their inoperative position;

Fig. 5 is a similar fragmentary view, the parts being shown in their operative position;

Fig. 6 is an enlarged vertical sectional view taken on line 6—6 in Fig. 4;

3

Figs. 7 and 8 are vertical sectional views taken respectively on lines 7—7 and 8—8 in Fig. 4;

Fig. 9 is a side elevational view, partly in section, of a tapered cam member;

Fig. 10 is a perspective view of a head band as it appears prior to being subjected to the action of the present apparatus;

Fig. 11 is a similar view thereof as it appears after being subjected to the action of the apparatus;

Fig. 12 is a side elevational view of a typical cap in the manufacture of which the novel apparatus of the present invention may be employed.

With particular reference now to Figs. 1, 2, 3, and 4, the apparatus comprising the invention is generally indicated by numeral 15, and a support whereon it is mounted, by numeral 16. The latter may be any suitable base member, bench or the like, a table top 18 supported on legs such as indicated at 20, being shown.

The apparatus 15 includes a pair of spaced, substantially rectangular blocks 22 each provided with an integral, rearwardly extending flange or base portion 24 rigidly secured to said support 16 as by tap bolts 26, or otherwise. As shown in Figs. 1 and 3, the forward portion of each block 22 projects beyond the forward face of said support.

Said device also includes a head band supporting member of arcuate form designated 28, a pointer assembly generally indicated 30, a plurality of auxiliary guage members each designated 32, a pair of similar primary guage assemblies each generally indicated 34, a pair of oppositely positioned perforating assemblies each generally designated 36, a cam and lever assembly 38 for motivating the perforating assemblies, and other elements associated with the operation thereof as will appear.

Each of the blocks 22 has formed therein a longitudinal slot 40 extending from the front face thereof rearwardly a distance adapted to accommodate any and all standard head band widths of uniform caps, the rearward vertical faces of said slots being designated 42 in Figs. 1 and 3.

As shown in the drawings, the slots 40 are generally angularly formed relative to the vertical longitudinal centerline of each block 22, and their forward, or head band receiving faces are beveled as at 44 to facilitate entry of said band.

Adjustably disposed for forward or rearward positioning in each slot 40, is the depending finger 46 of an angular member 48 included in a primary guage assembly 34. Said member also includes an integral horizontal portion 50, which, as shown in Fig. 1, is provided with an elongated slot 52 through which passes the threaded shank portion of a manually rotatable screw 54, whereby the member 48 may be positioned at a selected distance from the vertical face 42, as is manifest.

In order to add rigidity to the depending free finger or stop member 46, a horizontally disposed abutment screw 56 extends through the rear portion of block 22 and into slot 40 to engage against the rear face of said finger. A lock nut 58 is provided.

Each block 22 has also formed therein a pair of transverse bores 60 and 62 which are in alignment, as shown in Figs. 4 and 5. Into the bore 60 extends the reduced hollow stem portion 64 of an open-ended cylinder 66 included in the assembly 36. Said cylinder has an integral flange portion 68 whereby it is secured to block 22 as by tap bolts 70.

Pressfitted into bore 62 is a female die member 72 which seats against a shoulder 74 formed by

4

the reduced outer end portion 76 of said bore, as illustrated. Preferably the inner face of said die is of convex contour as indicated at 77.

As best seen in Figs. 4 and 6, the inner end portion of each cylinder 66 is provided with aligned vertical slots 78 to accommodate the central body portion 80 of a lever 82 included in the assembly 38. Each lever 82 is pivotally mounted at one end as at 84, in the bifurcated end of a horizontal supporting member 86 rigidly secured to block 22 as by tap bolts 88, or otherwise.

Reciprocable within each cylinder 66 is a piston 90 which includes a reduced, laterally projecting stem portion 92, which will hereinafter be termed a perforating pin. Normally, that is in the inoperative position of the device portrayed particularly in Fig. 4, the rounded extremity 93 of each pin 92 lies slightly inwardly from the inner wall of slot 40, being so maintained by a compression spring 94 about a portion of said pin and interposed between wall 96 of said cylinder, and said piston. Each pin 92 is slidably supported in hollow stem portion or guide 64, and the external diameter thereof is slightly greater than the internal diameter of the bore 97 of the dies.

The inner end portion of each piston 90 is also vertically slotted or bifurcated as at 98, to accommodate portion 80 of adjacent lever 82. Said portion 80 of each lever has formed therein an elongated slot 100, and passing through this slot, and extending into aligned apertures 102 in said piston, is a horizontally disposed pin 104, as particularly shown in Fig. 6.

Depending from the body portion 80 of each lever 82, and integral therewith, is an arm 106, the lower extremities of these arms being connected by means of a tension spring 108. The spring 108, though not absolutely essential, has been found to have a stabilizing effect during operation, and in addition, to aid the springs 94 in withdrawing the perforating pins from the dies, as will appear.

Each of the levers 82 includes an angular cam edge 110 terminating in a rounded portion 112 which merges into the edge portion of arm 106. Normally, under the combined influence of springs 94 and 108, the rounded edges 112 rest against the lower extremities of inclined cam faces 114 formed in a cam member 116, shown per se in Fig. 9.

As there seen, and with reference also to Fig. 4, the cam faces 114 are so formed as to also provide vertical guideways 118 for the levers 82. That is to say, the width of said guideways is such as to slidably receive the cam edges 110 of said levers, so that when the cam element 116 is reciprocated, positive and smooth operation will ensue.

The upper end of cam member 116 is preferably bifurcated, and has a pivotal connection 120 with the forward free end of a link 122 the rear end of which is pivotally supported as at 124 between a pair of brackets 126, bolted as shown, or otherwise secured to the supporting base 16.

Intermediate the ends of the link 122, there is pivotally connected, as at 128, a clevis 130 rigid with an upwardly projecting shaft 132, whereby the cam 116 may be vertically reciprocated a predetermined distance in either direction.

It is again here noted, that the link 122, and with it the cam 116, may be reciprocated either manually or mechanically, so that the particular arrangement illustrated is to be considered exemplary only.

In other words, the shaft 132 may be the lower

end of a piston rod depending from an air cylinder of any well known design, wherein a down stroke followed by an up stroke constitutes a cycle. Again, said shaft may be reciprocated by means of a foot treadle arrangement, or by mechanism similar to that employed in the operation of punch presses, and so on, as is understood.

The head band supporting member 28 includes a substantially semi-circular trough-like body portion 134 terminating in outstanding horizontal flanges 136. By means of tap bolts 138 passing through holes in said flanges, the member 28 is rigidly secured to the undersides of the forwardly projecting portions of blocks 22, as best seen in Fig. 3.

On the vertical centerline of the apparatus, the pointer assembly 30 is adjustably mounted on the member 28 as portrayed especially in Fig. 8. This assembly includes a horizontal base portion 140 and a vertical extension 142. The base portion is provided with elongated slots 144 through which pass the shanks of set screws 146 into engagement with threaded apertures provided in the arcuate body 134. The upward extension 142 is vertically slotted, as at 148, for the reception of the rear end 150 of a pointer or indicator 152 pivotally mounted on a pin 154, as shown.

Normally, the pointer 152 occupies the horizontal position shown, with the flat lower edge 156 of its rear end portion 150 resting upon the bottom surface 158 of slot 148. Preferably, the underside 160 of the pointer is beveled upwardly from the rear to the front end thereof.

As previously stated, a plurality of auxiliary guage assemblies 32 are also mounted in spaced relation on the arcuate body portion 134 of member 28.

Each of these, as seen particularly in Fig. 7, includes a flat base portion 162, and a reversely bent forwardly projecting free end portion 164 terminating in an upwardly flared lip portion 166. Elongated slots 168 are provided in the base portion 162, and therethrough pass screws 170 into engagement with the body portion 134 of the member 28.

From the foregoing, it should be evident that the assemblies 30, 32, and 34 are horizontally shiftable either rearwardly or forwardly, and that when they are positioned in proper vertical registry relative to one another, they may be so maintained indefinitely by the means shown and described.

It should also be evident, that the apparatus may be adjusted to perforate head bands of various widths, and to form perforations therein at selected points relative to the rim portions thereof.

Operation

It will be assumed that the manufacture of a quantity of uniform caps, such as that illustrated in Fig. 12, is contemplated. It will be further assumed that the strap A has an overall length of eleven and one-half inches, so that the apertures for each fastening element suggested at B should be spaced apart exactly eleven inches. It will also be assumed that the band C, regardless of head size, is two and one-eighth inches wide, and that according to specifications, the apertures are to be located exactly one and one-half inches from one rim of said band, with each of them five and one-half inches from an indicated mark, which in another operation also serves as

a guide for the attachment of an insignia holder or the like.

In other words, the pointer assembly 30 is employed only in that type of cap wherein it is not only requisite that the apertures herein referred to are located a prescribed distance apart, but also that they be equidistant from a designated point on the periphery of the band.

Assuming therefore, that the required number of head bands C have been previously assembled, and that an indicating notch or mark D, as in Fig. 10, appears on the inner periphery of each band adjacent the bottom edge thereof, proper adjustments of the apparatus are made before beginning perforating operations.

First, the primary guage assemblies 34 are so positioned that the front faces of the depending fingers 46 are spaced one and one half inches from the transverse vertical centerline of the perforating assemblies 36.

Thereupon a head band C may be inserted into the slots 40, as suggested by broken lines in Fig. 2, whereupon the auxiliary guage members 32 may be adjusted and locked in position. Finally, the pointer assembly 30 will be adjusted so that its free extremity will lie directly above the indicating marks D, as is understood.

With the guage assemblies rigidly secured by the means already described, the apparatus is now set up for efficient operations, which may be repeated indefinitely. Obviously, the distance obtaining between the axial center lines of the two die members 72 along the inner periphery of member 28 is eleven inches in the apparatus illustrated, this being the generally standard distance required. Should it be desirable to increase this distance, shims may be interposed between the bottom faces of blocks 22 and the flanges 136.

To perforate a head band, the operator inserts it into the slots 40 manually, sliding the lower integral segment thereof along the member 28 until the leading rim of the band simultaneously abuts the fingers 46 and the rebent portions 164 of the guage assemblies 32.

The beveled underside 160 of the pointer 152, and its pivotal mounting which permits it to swing upwardly, facilitate entry of the band with the indicating mark D in registry with the forward extremity of said pointer. The beveled faces 44 facilitate entry of the band into the slots 40. Thus band C is now supported in position by the apparatus, as shown in broken lines in Fig. 2.

Thereupon, the operator, either by manual or mechanical means as described, effects a down stroke of the cam member 116, followed immediately by an up stroke thereof to complete a cycle.

On the down stroke, the cam faces 114 ride along the edges 110 of the levers 82 to force the pair of pistons 90 outwardly against the influence of springs 94 and 108.

This action causes each of the pins 92 to punch out a small circular segment of the laminated materials of which the band is formed. The final stage of this action is portrayed in Fig. 5, wherein the head band C is shown, in the interest of clarity only, as though formed of a single piece of material, and wherein the punched out segments are designated E.

As the cam member 116 now returns to its upper position, the combined action of springs 94 and 108 withdraws the pins 92 from the female dies 72, the separated segments E however, remaining therewithin.

The now perforated band C is quickly removed, and another inserted, to repeat the operation. Succeeding segments E propel the preceding segments outwardly in the hollow die members 12 until, as suggested by broken lines in Fig. 5 at 5 the right, they are discharged via openings 16.

From the foregoing description and the drawings, it should be apparent that the instant invention provides a novel apparatus whereby great quantities of laminated head bands or similar articles may be positively and accurately apertured with dispatch.

The appearance of the band C, after having been subjected to the action of the device, may be seen in Fig. 11, where the perforations which 15 were formed therein are each designated P.

It is manifest that although the instant apparatus has been designed primarily to perforate head bands for uniform caps, sun helmets, and the like, it may also be employed to perforate 20 bands of relatively thin metal, plastic, and so on.

The embodiment illustrated also obviously admits of modifications without departure from the broad concepts of the invention, the scope of which is to be limited only by the appended 25 claims.

What I claim is:

1. Apparatus for punching holes in the head band of a uniform cap at two points circumferentially spaced a selected distance from one another, with each point also spaced a selected distance from one rim of the band, said apparatus including: a supporting base; a pair of horizontally spaced substantially rectangular block members mounted on the base, the forward portion of each block projecting beyond the forward face of said base; an arcuate member removably secured at its ends to the underside of the projecting portions of said blocks for supporting said band along the lower arcuate segment thereof; a longitudinal slot in each of said blocks for the reception of a segment of the band adjoining said lower arcuate segment; a primary guage assembly associated with each block for engaging against a rim portion of those segments of said band which are disposed in the longitudinal slots aforesaid; a plurality of auxiliary guage members associated with said arcuate member for engaging against a rim portion of that segment of the band which is supported on the arcuate member; a pair of oppositely disposed perforating assemblies each supported by one of said blocks and including a reciprocal piston having a laterally projecting pin integral therewith for simultaneously perforating the two segments of the band which are disposed in said longitudinal slots; a pair of levers each pivotally mounted at one end to a support rigid with one of said blocks and having an elongated slot on pin connection with the piston of one of the perforating assemblies; and a vertically reciprocable cam member to simultaneously swing said levers in opposite directions about their pivotal mountings.

2. Apparatus for punching holes in the head band of a uniform cap at two points circumferentially spaced a selected distance from one another, with each point also spaced a selected distance from one rim of the band, said apparatus including: a supporting base; a pair of horizontally spaced substantially rectangular block members mounted on the base, the forward portion of each block projecting beyond the forward face of said base; an arcuate member removably secured at its ends to the underside of the projecting portions of said blocks for supporting said 75

band along the lower arcuate segment thereof; a longitudinal slot in each of said blocks for the reception of a segment of the band adjoining said lower arcuate segment; a primary guage assembly associated with each block for engaging against a rim portion of those segments of said band which are disposed in the longitudinal slots aforesaid; a plurality of auxiliary guage members associated with said arcuate member for engaging against a rim portion of that segment of the band which is supported on the arcuate member; a pair of oppositely disposed perforating assemblies each supported by one of said blocks and including a reciprocal piston having a laterally projecting pin integral therewith for simultaneously perforating the two segments of the band which are disposed in said longitudinal slots; a pair of levers each pivotally mounted at one end to a support rigid with one of said blocks and having an elongated slot on pin connection with the piston of one of the perforating assemblies; a vertically reciprocable cam member to simultaneously swing said levers in opposite directions about their pivotal mountings for actuating each piston in one direction on the downstroke of the cam; and a tension spring connecting the free extremities of said levers for actuating each piston in the opposite direction on the upstroke of said cam.

3. The apparatus set forth in claim 2 wherein the longitudinal slot in each block is angularly formed relative to the vertical longitudinal centerline of the block; and wherein the forward edges of said slots are bevelled to facilitate entry of said band segments thereinto.

4. The apparatus set forth in claim 2, wherein the primary guage assembly associated with each block comprises: an angular member including a horizontal portion and a depending finger portion integral therewith, said horizontal portion resting on the top surface of the block, said finger portion extending into the longitudinal slot in said block; an elongated slot formed in said horizontal portion; a screw passing through said slot and into engagement with a threaded aperture in the block for securing said angular member in selected position relative to the front face of the block; a horizontally disposed abutment screw extending through the rear portion of the block for engaging against the depending finger aforesaid; and a nut for locking said screw in position.

5. The apparatus set forth in claim 2, wherein in each of the auxiliary guage members associated with the arcuate band supporting member includes: a flat base portion and a free reversely bent forwardly projecting portion integral therewith, said base portion lying along the underside of, and said free portion occupying a plane parallel with but above said band supporting member; an upwardly inclined lip formed on the extremity of the free portion of said element; at least one elongated slot formed in the base portion; and a screw passing through said slot into engagement with a threaded aperture in said band supporting member for locking the gauge in a selected position.

6. The apparatus set forth in claim 2, wherein in each of said perforating assemblies includes: an open-ended cylinder having a reduced stem portion extending into a first horizontal bore provided in the block which supports said assembly; a female die having a convex face portion and seated in a second horizontal bore provided in said blocks, both said bores being in alignment and opening at one end into said

longitudinal slot of the block; a piston reciproca-
ble in said cylinder toward and away from said
die member; a pin having a rounded extremity
projecting laterally from the piston and recipro-
cal therewith to perforate the band disposed in
said slot as the pin passes through said band and
strikes the convex face of the female die afore-
said; a compression spring interposed about a
portion of said pin between the piston and a
wall of the cylinder for normally maintaining said
pin withdrawn from said die; and a vertical slot
in said piston aligned with a pair of similar slots
in said cylinder for accommodating that portion
of the lever aforesaid which has a loose connec-
tion with said piston.

JOSEPH G. PESSINA.
